Des. 206,583
Patented Jan. 3, 1967

206,583

TRAVEL TRAILER

Georges Etienne Christin, Marnes-la-Coquette, France,
assignor to Etablissements Bertrand Faure, Peteaux,
France, a corporation of France

Filed Mar. 14, 1966, Ser. No. 1,460

Claims priority, application France Sept. 30, 1965

Term of patent 14 years

(Cl. D14—3)

FIGURE 1 is a side elevational view of a travel trailer embodying my new design with the end closure thereof in its partially opened condition;

FIGURE 2 is a top plan view thereof;

FIGURE 3 is a rear end view thereof;

FIGURE 4 is a front end view thereof;

FIGURE 5 is a rear and side perspective view of said travel trailer with the end closure thereof in its closed condition;

FIGURE 6 is a front and side perspective view thereof; and

FIGURE 7 is a side elevational view thereof.

The dominant features of the design are shown in solid lines.

I claim:

The ornamental design for a travel trailer, as shown and described.
